CLAIM

The ornamental design for exercise device, as shown and described.

DESCRIPTION

FIG. 1 is a top, front, right-side perspective view of a first embodiment of the exercise device of the present disclosure; FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and

FIG. 8 is a top, front, right-side exploded perspective view thereof showing unclaimed and environmental matter in broken line.

FIG. 9 is a top, front, right-side perspective view of a second embodiment of the exercise device of the present disclosure;

FIG. 10 is a front elevation view thereof;

FIG. 11 is a rear elevation view thereof;

FIG. 12 is a left-side elevation view thereof;

FIG. 13 is a right-side elevation view thereof;

FIG. 14 is a top plan view thereof;

FIG. 15 is a bottom plan view thereof; and,

FIG. 16 is a top, front, right-side exploded perspective view thereof showing unclaimed and environmental matter in broken line.

The shade lines shown in the drawings indicate the character and contour of surfaces represented and should not be confused with surface ornamentation.

The broken lines shown in the drawings are for the purpose of illustrating portions of the exercise device that form no part of the claimed design.
